Primary Examiner — Alison M Ofstun(74) *Attorney, Agent, or Firm* — CAIP; Xia Li(57) **CLAIM**

The ornamental design for a hair clipper, as shown and described.

DESCRIPTION

FIG. 1 is a perspective view of a hair clipper showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is bottom plan view thereof;

FIG. 9 is an enlarged view of portion “9” shown in FIG. 1; and,

(Continued)

FIG. 10 is an enlarged view of portion “10” shown in FIG. 2.

The broken lines in the drawings depict portions of the hair clipper that form no part of the claimed design.
